Bayani S. Lagdan, Legaspi City, Republic of the
Philippines

Application February 5, 1954, Serial No. 28,864

Term of patent 3½ years

(Cl. D71—1)

To all whom it may concern:

Be it known that I, Bayani S. Lagdan, a citizen of the Philippine Republic, residing at Legaspi City, Philippine Republic, have invented a new, original, and ornamental Design for an Airplane, of which the following is a specification, reference being had to the accompanying drawing, forming a part hereof.

Figure 1 is a top plan view of an airplane, showing my new design;

Figure 2 is a front elevational view;

Figure 3 is a rear elevational view;

Figure 4 is a side elevational view; and

Figure 5 is a bottom plan view.

I claim:
The ornamental design for an airplane, as shown.
